UNITED STATES PATENT OFFICE.

CLYDE S. WRIGHT, OF TOLEDO, OHIO, ASSIGNOR TO THE NATIONAL SUPPLY COMPANY, OF TOLEDO, OHIO, A CORPORATION OF OHIO.

BREAKING-OUT TONGS.

1,114,663.

Specification of Letters Patent. Patented Oct. 20, 1914.

Application filed November 7, 1913. Serial No. 799,710.

To all whom it may concern:

Be it known that I, CLYDE S. WRIGHT, a citizen of the United States, residing at Toledo, in the county of Lucas and State of Ohio, have invented new and useful Improvements in Breaking-Out Tongs, of which the following is a specification.

My invention relates to what are known as breaking-out tongs, that is, tongs for breaking or unscrewing the joints of pipes or casings as they are drawn from a well.

The joints or couplings between the ends of pipes are set up very tight, and the weight to be turned is very great. The lower end of the coupling to be unscrewed rests on an elevator or other support and the whole line of pipes in the well are suspended on the said coupling. The tongs not only have to overcome the force by which the joint is held together, but they have also to rotate the suspended pipes which may weigh several tons and to overcome the friction between the coupling and the elevator or equivalent support. In the performance of the work of unscrewing the couplings, the tongs become stuck very tight and are very hard to get off. It is the object of my invention to provide easily operated means for releasing the tongs from couplings or pipes.

Referring to the accompanying drawings, Figure 1 is an elevation of an apparatus embodying my invention, parts being broken away; Fig. 2, a plan view of the same, showing the parts as they are when unscrewing a coupling; Fig. 3, a similar view, showing one of the tongs released and ready for removal; Fig. 4, a similar view showing the tongs removed from the coupling, or ready to be applied thereto; and Fig. 5, a section on the line V—V, Fig. 2.

On the drawings, 1 represents a rotary horizontal table driven by the shaft 2 by means of the intermediate bevel-gearing 3. This table is located over a well so that the pipe 4 may be raised or lowered through the same in a manner well known. The pipe 4 is composed of many sections connected end to end by pipe-couplings or joints. I have shown two sections of the pipe 4 connected by a pin and box coupling, the pin end or section being marked 5, and the box end or section being marked 6. The coupling section has the tapered thread end or pin 7

screwed into the corresponding tapered hole 55 or box in the upper end of the section 6. The sections 4 are screwed respectively into the upper end of the pin section 5 and the lower end of the box-section 6. The lower end of the coupling rests on the usual elevator 7 which rests upon the top of the table and supports all the sections of pipe connected to the coupling seated thereon, 8 being two of the links by which the pipe is raised or lowered. The weight of the pipe 65 sections and couplings may be several tons and the friction between the coupling and the elevator 7 may be very great. Furthermore, the force required to unscrew the sections 5 and 6 is very considerable. Accordingly, the rotary table is utilized as a source of power for actuating the tongs.

9 represents the handle of the upper pipe tongs A carrying the pivoted outer jaw 10, suspended by the bolt or link 11 on any convenient support. The handle 9 is prevented from moving from left to right by the post 12 or other means, such as a cable or chain 13 attached to the handle and a fixed support. The jaws of the upper tongs engage 80 the section 5 of the coupling, and are applied so as to resist the turning of the said section from left to right.

14 represents the handle of the lower pipe tongs B, carrying the pivoted outer jaw 15. The jaws of the tongs are applied to the section 6 of the coupling so as to rotate the same and the sections of the pipe 4 below the elevator 7 from left to right.

16 is the vertical driving post carried by 90 the table. The hub or sleeve 17 oscillates on the post 16 and is provided with the horizontal lugs or ears 18, between which one end of the toggle link 19 is connected by the pivot 20. The other end of the link 19 has 95 the pair of ears 21 between which the outer end of the handle 14 is connected by the pivot 22. The lower end of the sleeve 17 has the extension 23 to which the handle 24 is secured by one or more set screws 25.

26 is a collar on the post 16 below the sleeve and handle to hold them and the tongs at the desired level. The collar is secured to the post by one or more set screws 27.

The link 19 extends out beyond the sleeve 105 17, the end thereof connected to the ears 18 being curved or hooked back toward the center of the table so that the pivot 20 may be

swung by the handle 24 at least into line with a line connecting the centers of the post 16 and the pivot 22. The pivot 20 may swing so that the pivot 20 will pass slightly beyond the said line, that is, slightly past the dead center of the pivot 20 with respect to the post 16, as shown on Fig. 2.

With the parts as shown on Figs. 1 and 2 and the table 1 rotating with the arrow thereon, the tongs B will cause the section 6 with all the pipe suspended thereon to be turned from left to right, thereby unscrewing the section 6 from the section 5. When the sections 5 and 6 are unscrewed, the lever 24 is swung out away from the center of the table as shown in Fig. 3 which permits the tongs B to be readily and easily released from the section 6. In fact, the throwing of the lever back to the position shown on Fig. 3 causes the link 19 to push the handle 14 back, so as to move the handle jaw or the pivoted jaw or both away from the coupling. The tongs B can then be swung to the right, that is, away from the coupling as shown on Fig. 4, ready to be swung back when another coupling has been brought up by the elevator 7 above the top of the table 1.

I have shown the wrenches applied to two sections of a coupling, but it is clear that where the coupling is made of only one piece one of the tongs may engage the coupling and the other the section of pipe screwed into the upper end of the same. It is also evident that, by turning the tongs A and B bottom side up and placing the handle 9 on the opposite side of the post 12, the sections 5 and 6 could be screwed together by reversing the rotation of the table.

It will be observed from Fig. 2 that when the toggle links 18 and 19 are in locking position, that is, with the pivot 20 in the dead center position with respect to the pivots 16 and 22, the links 18 are prevented from swinging too far toward the center of the

table, by engagement of the link 19 with the 45 sleeve 17.

I claim—

1. In an apparatus for turning one threaded member with respect to a companion threaded member, means for preventing the turning of one member, tongs for turning the other member, means having rotary travel around the members, a toggle mechanism connecting the tongs and the rotary means, and means for operating the toggle 55 mechanism.

2. In an apparatus for turning one threaded member with respect to a companion threaded member, means for preventing the turning of one member, tongs having an 60 operating lever for turning the other member, a device having rotary travel around the members, a driving post on the rotary device, toggle links connected between the lever and the post, and means for operating 65 the links.

3. In an apparatus for turning one threaded member with respect to a companion threaded member, means for preventing the turning of one member, tongs for turning the other member, a pair of toggle links having one end of each pivotally connected together, the remaining end of one link being pivotally connected to the tongs, means having rotary travel around the said members and having the remaining end of the 75 other link pivotally connected thereto, and means for moving the links so that the connecting pivot between the links shall come into the dead center position with respect to 80 the other two pivots.

Signed at Toledo, Ohio, this 3rd day of November 1913.

CLYDE S. WRIGHT.
